UNITED STATES PATENT OFFICE.

MILES M. KELLOGG, OF ENCINITAS, CALIFORNIA.

FOUNTAIN PAINT-BRUSH.

1,376,702.

Specification of Letters Patent.

Patented May 3, 1921.

Application filed June 24, 1920. Serial No. 391,480.

To all whom it may concern:

Be it known that I, MILES M. KELLOGG, a citizen of the United States, residing at Encinitas, in the county of San Diego and State 5 of California, have invented certain new and useful Improvements in Fountain Paint-Brushes; and I do declare the following to be a full, clear, and exact description of the invention, such as will enable others skilled 10 in the art to which it appertains to make and use the same.

This invention relates to an improved fountain-brush which is especially designed to be used as a paint brush, although it is 15 not to be restricted to such use.

An object of the invention is to provide a brush of the above type wherein the handle being hollow, serves as a container for a quantity of paint which is dispensed therefrom onto the bristles of the brush, such dispensing being controlled by a valve which is in turn operated by mechanism on the exterior of the handle within convenient distance of the user's thumb, thus dispensing 20 with the old way of employing a bucket and separate brush. This new method is a great deal more convenient, and prevents soiling 25 of the user's hands, etc.

Another object of the invention is to provide a device of the above mentioned character in which the valve operating mechanism serves as a plunger which keeps the passage 30 between the handle and brush open at all times so that the paint will flow freely when 35 the valve is open.

A further object of the invention is to provide a device of the above mentioned character wherein the construction is such that the paint will be freely applied to the brush even 40 though the bristles are flexed under pressure exerted thereon when the brush is in use.

Other objects and advantages of the invention will be apparent during the course 45 of the following description.

In the accompanying drawings forming a part of this specification and in which like numerals are employed to designate like parts throughout the same:—

Figure 1 is a central vertical sectional 50 view, partly in elevation, of a device constructed in accordance with my invention.

Fig. 2 is a top plan view thereof.

Fig. 3 is a view of the lower end of the brush taken on the plane of the line 3—3, 55 looking in the direction of the arrows.

Fig. 4 is a view illustrating a modified form of the valve actuating mechanism.

In carrying out my invention I employ a tubular tapered handle 1 which is open at its opposite ends, and which when closed by 60 parts to be hereinafter described, forms a container for a quantity of paint or other liquid. The numeral 2 designates the brush-head which is detachably connected to, and closes one end of the tubular handle. Embedded in this brush is a tube 3, the inner end of which extends into the interior of the handle and provides a valve seat 4 with which a valve 5 coacts. This tube extends into the brush a sufficient distance to 70 apply paint freely to the bristles of the brush, and it is contracted at its outer end as shown at 6 to decrease the flow of paint therethrough. Connected in any suitable manner to this contracted end of the tube 75 is a nozzle 7 of rubber or other resilient material which is likewise contracted at its outer end. By this construction it will be seen that the passage of the paint will never be obstructed by the bristles of the brush 80 crossing the outlet and closing it, because this nozzle being flexible will follow the bristles to the various angles which they assume when pressure is exerted thereon during 85 the course of painting.

The valve is actuated by means of a rod 8 which is connected thereto at its lower end and extends throughout the entire length of the handle and through the opening in the cap 9. It is to be noted that a portion of this 90 rod extends into the tube 3, this portion being designated by the numeral 10. The purpose of this construction is to insure that the tube will never become clogged by thick paint. It is obvious that during the operation 95 of the valve, this portion 10 of the rod will act as a plunger and will thus force any particles of paint through the tube. If desired the extremity of the portion 10 of the rod may be enlarged to form a head 11 so 100 that the latter will strike the walls of the tube and insure proper cleaning thereof. Movement is imparted to the rod 8 by means of an L-shaped lever 12 which is pivotally mounted at 13 on a cap 9. The connection 105 between the lever 12 and rod 8 consists of a nut 14 which forms a stop, beneath which the looped end 15 of the rod 12 is disposed. It is obvious that by exerting pressure on the free end of the lever 12 will rock the same 110

on its pivot and impart movement to the rod 8, causing the valve 5 to become unseated. In order to retain the valve normally closed, I provide a coiled spring 16 which surrounds the rod 8 between the adjustable shoulder 17 and the under face of the cap 9. This spring not only serves to retain the valve normally closed but it also serves to seat the gasket or other suitable packing member tightly 10 against the opening in the cap through which the rod 8 extends, thus preventing leakage. Paint may be placed within the handle by removing the cap 9 or it may be more conveniently placed therein by means of the 15 neck 18 which I provide and which is closed by a stopper 19.

The operating mechanism may, if desired, be arranged in the interior of the handle. In Fig. 4 I have shown such an arrangement, 20 and for the sake of clearness I have made use of the same numerals to indicate like parts in this figure, wherein 8 indicates the valve actuating rod and 12 the L-shaped operating lever. In this arrangement the L-shaped lever extends through the wall of the handle and is mounted therein for rocking movement as shown at 20. Instead of the type of connection between this lever and the rod 18 employed in the already described 25 device, I pivot the lever 12 and rod 8 together as shown at 21, the rod 8 working through a guide 22 which also serves as a shoulder, against which one end of the coiled spring 16 abuts, the other end of the latter engaging 30 the shoulder 17 in the same manner as that set forth in the other form of my device. In this form of device I make use of another coiled spring 23, the purpose of which is to retain the gasket 24 in position, 35 thus preventing leakage.

When it is desired to supply the bristles of the brush with paint, this may be accomplished by lifting the valve 5 from its seat, this being done by pressing the thumb 40 against the free ends of the lever 12 which action imparts a rocking motion to the latter and at the same time moves the rod 8 longitudinally which imparts the desired movement to the valve, as is obvious. No 45 matter how much pressure is placed upon the bristles of the brush, causing them to become flexed as indicated in dotted lines in Fig. 3, the supply of paint will never be cut off because the nozzle 7 will move with the 55 bristles in the manner there illustrated.

From the foregoing description taken in connection with the accompanying drawings, it is believed that persons familiar with such devices will be enabled to obtain a 60 thorough understanding of my device, there-

fore, further description is deemed unnecessary.

It is to be understood that the form of my invention herein shown and described is to be taken as the preferred form of the same 65 and that various minor changes in the shape, size, and arrangement of parts may be resorted to without departing from the spirit of the invention or the scope of the subjoined claims. 70

I claim as my invention:—

1. A fountain-brush comprising a hollow handle to contain a liquid to be dispensed, a brush-head connected to one end of the handle, a tube embedded in the brush-head, 75 the inner end thereof extending beyond the head into the interior of the handle, forming a valve seat, a valve co-operative with said seat, a plunger rod carried by the valve and extending into the tube, the free end 80 thereof being enlarged to engage the inner wall of the tube to clean the same, and means for actuating the valve.

2. A fountain-brush comprising a tubular handle, open at its opposite ends, a brush-head threaded into and closing one end, a screw cap closing the opposite end, a tube embedded in the brush-head, the inner end of the tube extending into the handle and providing a valve seat, a valve for co-operation with the seat, a valve actuating rod extending through the handle, an L-shaped pivotally mounted lever connected to the rod, a shoulder on the rod, and a coiled spring surrounding the rod bearing on the 90 shoulder and against said screw-cap. 95

3. A fountain-brush comprising a handle, open at its opposite ends, a brush-head threaded into one end, an apertured screw-cap closing the opposite end, a tube embedded in the brush-head, having its inner end projecting into the handle, forming a valve seat, a valve coacting with said seat, a valve actuating rod connected to the valve and extending through the aperture in the 100 cap and beyond the latter, an L-shaped operating lever pivotally connected between its ends to the cap, one end thereof being connected to the extended portion of the actuating rod, a shoulder on the inclosed portion of the said actuating rod, a gasket ring surrounding said rod in a position to cover the aperture in the cap, and a coiled spring surrounding the rod between the shoulder and the gasket to normally retain the gasket 110 in contact with the cap and also to retain the valve closed. 115

In testimony whereof I have hereunto set my hand.

MILES M. KELLOGG.
